CLAIM

The ornamental design for a wireless remote control, as shown and described.

DESCRIPTION

FIG. 1 is a perspective view of a wireless remote control showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, left side perspective view thereof.

Any shading and cross-hatching are not features of the design but are utilized to illustrate the surface contours of the wireless remote control design in the drawings.

The broken lines in the drawings depict portions of the wireless remote control that form no part of the claimed design.
